UNITED STATES PATENT OFFICE.

GIACOMO ALLEGRETTI, OF STOCKTON, CALIFORNIA.

METHOD OF AND APPARATUS FOR MAKING PHONOGRAPH RECORDS.

Application filed January 22, 1921, Serial No. 439,188. Renewed December 28, 1922.

To all whom it may concern:

Be it known that I, Giacomo ALLEGRETTI, a citizen of the United States, residing at Stockton, county of San Joaquin, State of California, have invented certain new and useful Improvements in Methods of and Apparatus for Making Phonograph Records; and I do declare the following to be a full, clear, and exact description of the same, reference being had to the accompanying drawings, and to the characters of reference marked thereon, which form a part of this application.

This invention relates to improvements in phonograph-record making, the principal object being to devise what may be termed a phono-engraving process, and an apparatus by means of which the process may be carried out.

By means of my invention, master phonograph records may be produced directly and without the necessity of first recording the sounds on a soft wax, which necessitates a number of subsequent operations before the individual records are made.

My method may therefore also be used by individual owners, who may desire to make their own records, which heretofore to my knowledge has been impractical, at least without incurring considerable expense and in a complicated way.

I am also enabled to regulate the depth of cutting of the record, so that the volume of sound finally reproduced may be varied without necessarily increasing the original sound-volume, the vibrations produced by which cause the record to be cut.

Further, I am not limited to the use of the wax composition now generally used for records, but may employ any material which can be etched by acids and which may be made in a form suitable for my purpose.

Briefly, I contemplate, as indicated in the preceding paragraph, etching the surface of a blank by means of acids suitable for the purpose, the acid being deposited on the blank in minute drops of various sizes, which then eat into the blank to corresponding and varying depths, the depositing of the acid being regulated and controlled by the strength of the sound waves or vibrations received into a transmitter, which is provided with means cooperating with the

acid to cause it to be deposited as aforestated.

The above described method is employed for making records for individual purposes. For making master records, the same apparatus is used in the same manner, but the fluid used, instead of etching or eating into the blank, stays on the surface, hardening thereon, so that female records as universally used can be made directly therefrom.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views.

Fig. 1 is a sectional view of one form of sound-vibration transmitter.

Fig. 2 is a greatly enlarged fragmentary section of the recording tip or point.

Fig. 3 is a sectional view of another form of the device.

Fig. 4 is a greatly enlarged fragmentary section of a recording blank, showing the depositing of the liquid thereon.

Fig. 5 is a similar view showing the depressions made by the liquid in the blank after acting thereon.

Referring now more particularly to the characters of reference on the drawings, the numeral 1 denotes a circular base member supported for any desired and necessary swivel or other movement by an arm 2. Screwed onto the member 1 or otherwise adjustably mounted thereon for vertical movement is a cover 3 provided with a vibratory diaphragm 4 on the inner side thereof with which communicates a mouthpiece or sound-collecting horn 5.

Fixed to the base 1 and depending therefrom in vertical alinement with the axis of the horn 5 is a hollow tip or tube 6, preferably of glass or some material which is not affected by acids. Both the bore 7 of this tip and the outside as well taper down to the lower end to be as small as it is possible for it to be made.

Fixed to the diaphragm 4 and depending

into the bore 7 to a point adjacent the lower termination thereof is a pin 8 (Fig. 1) the bore being filled with a suitable acid 9, the amount of acid depending on the length of the record to be cut.

In operation, the tip is set into and guided by a groove 10 cut previously in the surface of a recording blank 11 which may be of any material desired which is suitable for the purpose and can be etched with an acid, the latter of course being one which has a great affinity for the particular record-material employed.

When sounds are produced and carried into the horn 5, the diaphragm of course vibrates correspondingly, as is well known. The pin 8 moving up and down with the diaphragm causes minute drops of the acid to be projected from the bottom of the tip 15 into the record groove 10, the size and length of these drops bearing a distinct relation to the magnitude and length of the sound-waves, as indicated at 12 on Fig. 4. If left undisturbed, these acid drops will etch or eat 20 into the blank to form depressions of various lengths and depths, as shown at 13 in Fig. 5, which correspond to the drops deposited, while the depth to which they cut (and consequently the volume of sound 25 which may be reproduced) depends on the time given the acid to act, and the strength thereof, these being matters to be determined.

If a soft record is desired, the acid may be wiped or cleaned off the record before it has expended its full strength. If a loud record is wanted, the acid is left to act for a longer period.

Also the angle at which the tip will strike 40 the record is a matter to be determined by experiment.

In the event that the droplets of any acid should exhibit a tendency to flow together, the viscosity, and hence the surface tension, 45 of the fluid may be increased by mixing it with another fluid of a heavier nature.

In the form of transmitter or recorder shown in Fig. 3, the main structure remains as before.

50 The pin 8^a however, does not extend to the bottom of the tip, but terminates a certain distance above the liquid, and is provided with a piston 14 at that point, which is spaced just sufficiently from the walls 55 of the tip-bore to allow air to pass thereby.

With this form of construction, the rapid vibration of the diaphragm causes vertical movement of the piston, which acts on the air below, which in turn causes the acid to 60 be projected from the end of the tip in minute drops, as heretofore explained.

In both types of the device, the tip-bore is in reality a capillary tube, which means that the liquid will not of itself flow from 65 the tip, but will if anything be normally

raised therein, until forced out by the action of the pin or piston.

By adjusting the cover 3 in either case, the positions of the pin and piston are varied accordingly, thus increasing or decreasing the intensity of their action on the fluid and regulating the size of the drops forced from the tip.

This feature is also brought into use to insure consistency in the size of the drops as 75 the amount of liquid carried by the tip.

It will be evident that it is not necessary to employ only circular and revolving record-blanks, but it may also be used to cut a record on the edge of a motion-picture 80 film, opening the way for "speaking" pictures, which have heretofore been attempted but with indifferent success.

In making master records, the etching fluid or acid is replaced by a substance such 85 as rubber dissolved in ether, which when projected from the tube and exposed to the air will solidify and harden, remaining on the surface of the blank without eating thereinto, as shown in Fig. 4. In this case 90 of course the blank must not be disturbed in any way until the substance thereon has solidified.

From the foregoing description it will be readily seen that I have produced such 95 a device as substantially fulfills the objects of the invention as set forth herein.

While this specification sets forth in detail the present and preferred construction of the device, still in practice such deviations 100 from such detail may be resorted to as do not form a departure from the spirit of the invention, as defined by the appended claims.

Having thus described my invention, what I claim as new and useful and desire to secure by Letters Patent is:

1. An apparatus for the purpose described including a diaphragm adapted to be acted on by the sound-waves produced, a capillary tube containing an etching fluid positioned under the diaphragm, said tube being placed immediately adjacent the record-blank to be etched, and means connected to the diaphragm and acting on the liquid for causing the liquid to be projected from the tube in minute drops bearing a distinct relation to the magnitude and length of the sound-waves causing the diaphragm to vibrate.

2. An apparatus for the purpose described including a diaphragm adapted to be acted on by the sound-waves produced, a capillary tube containing an etching fluid positioned under the diaphragm, said tube being placed immediately adjacent the record-blank to be etched, and a pin attached to and depending from the diaphragm into the tube and arranged to force the liquid from the latter and to the record-blank in minute drops depending on the magnitude and length of the 130

sound waves causing the diaphragm and pin to move.

3. An apparatus for the purpose described including a diaphragm adapted to be acted on by the sound-waves produced, a capillary tube containing an etching fluid, positioned under the diaphragm, said tube being placed immediately adjacent the record-blank to

be etched, a pin attached to and depending from the diaphragm into the tube, and means whereby the spacing of the diaphragm from said tube may be regulated at will.

In testimony whereof I affix my signature.

GIACOMO ALLEGRETTI.
